J. C. NORTON,
ROOF FLASHING AND METHOD OF CONSTRUCTING SAME,
APPLICATION FILED SEPT. 19, 1917.

1,261,276.

Patented Apr. 2, 1918.

Inventor:
Joseph C. Norton
by Merlin J. Saywell,
his attorney.

UNITED STATES PATENT OFFICE.

JOSEPH C. NORTON, OF CLEVELAND, OHIO.

ROOF-FLASHING AND METHOD OF CONSTRUCTING SAME.

1,261,276.

Specification of Letters Patent.

Patented Apr. 2, 1918.

Continuation of application Serial No. 111,522, filed July 26, 1916. This application filed September 19, 1917. Serial No. 192,087.

To all whom it may concern:

Be it known that I, JOSEPH C. NORTON, a citizen of the United States, resident of Cleveland, county of Cuyahoga, and State 5 of Ohio, have invented new and useful Improvements in Roof-Flashings and Methods of Constructing Same, of which the following is a specification, the principle of the invention being herein explained and 10 the best mode in which I have contemplated applying that principle, so as to distinguish it from other inventions.

My invention relates to roofing structures and has for its object the providing of a 15 waterproof joint between the vertical face of a wall and an adjacent flat roof surface, in an economical and efficient manner. The type of structures is usually referred to in the trade as a "roof flashing."

20 The said invention consists of means hereinafter fully described and particularly set forth in the claims.

This application is a continuation of application Serial No. 111,522, filed July 26, 25 1916.

The annexed drawings and the following description set forth in detail certain means embodying my invention, the disclosed means, however, constituting but one of 30 various mechanical forms in which the principle of the invention may be applied.

In said annexed drawings:

Figure 1 represents a perspective view of a fragmentary portion of a roof provided 35 with flashing embodying my invention.

Fig. 2 represents a vertical section, upon an enlarged scale, and taken at right angles to the plane of section of Fig. 1.

Fig. 3 represents a fragmentary section, upon a still further enlarged scale, and taken upon the plane of section of Fig. 2.

Fig. 4 represents a section similar to that of Fig. 3 and illustrating the structure in a more advanced state of construction.

Fig. 5 represents in perspective a fragmentary portion of the roof flashing element embodying one feature of my invention.

Fig. 6 represents a vertical fragmentary section of a wall illustrating one feature of 50 my invention in a modified form.

The illustrated embodiment of my invention comprises a strip 1 of suitable flexible roofing material or fabric such as waterproof roofing paper or the like. One edge 55 portion of this strip is reinforced by means

of a strip of sheet metal 2. This strip 2 is first laid upon the edge portion of the sheet 1 and bent around so as to inclose both sides thereof, forming a closed outer end 3. The sheet is then bent so that both sides form an 60 angle, preferably a right angle, forming two legs 4 and 5, the end of leg 5 being open and the outer side extending farther along the sheet than the inner, as shown in Fig. 5. The sheet 1 extends in the opening formed 65 between the two legs and by reason of the angular construction is fixedly secured therein.

The above operation is preferably and conveniently carried out in the shop prior 70 to the application of the element to the formation of a flashing. The strips are made of any desired and convenient length and width and may be piled up by "nesting" and thus conveniently transported or packed 75 in boxes. In this form it is readily available for the workman and in a finished condition for application.

In applying the above article of manufacture to the formation of a completed flashing in connection with a vertical wall such as the wall 6 and a roof such as the roof 7, Fig. 1, the mortar between two courses of brick is removed to form a longitudinal opening 8, Fig. 3. The outer leg 4 of the 85 reinforcement is then inserted into the openings thus formed, that part of the face 9 of the wall below the opening having first been treated with a suitable adhesive material such as asphalt or the like. The outer leg 4 90 is then inserted into the opening 8 and is then secured therein by any suitable means such as, for instance, wedges 10. These wedges are preferably driven in so as to be flush with the face of the wall, as shown in Fig. 4. After these wedges have been supplied, the remaining portion of the opening is then filled up with mortar. The depending portion 11 of the sheet is then pressed 95 against the face of the wall and secured thereto by means of the adhesive material. The roofing material 12 which covers the main part of the roof, is turned up as at 13 and covered by the lower portion 14 of the sheet 1, as shown in Fig. 2, the latter being 100 bent over in the corner to partially overlie the roof covering 12, so as to reinforce the angle as at 15 in said figure. Suitable adhesive material such as asphalt is used at 105 this point for completing the joint.

110

2
In the above described manner it will therefore be seen that a roof flashing which is waterproof and durable in its structure and which is very easily and simply applied, is obtained. This method of construction furthermore embodies the advantage of not requiring the services of any laborer other than one skilled in the application of roofing, since no particular skill is required for 10 the removal of the mortar, as will be readily understood.

In some types of flashing as, for instance, in that type in which the reinforcement is inserted by the masons during the building 15 of the wall 6, it has been found difficult, since the masons are not skilled in the art of applying roofing, to obtain the proper setting of the strips by such masons. Where, however, it is unnecessary to give any instructions of any kind to the masons regarding the structure of the flashing, as for 20 instance by my invention, this difficulty is entirely eliminated.

Should it be desired to apply my invention 25 in connection with a concrete wall, in which there are no brick courses, the desired apertures or openings 8 may be formed by inserting a strip 16 of wood or other similar material in the concrete during the process of pouring. This strip or these strips 30 may be removed after the concrete has set and for this purpose they are preferably made slightly wedge shaped, as shown in Fig. 6. The desired opening or openings 35 being thus formed in the concrete, the process thereafter is exactly similar to that previously described, as will be readily understood.

Having fully described my invention, 40 what I claim and desire to secure by Letters Patent is:

1. As an article of manufacture a coping roof flashing element formed prior to and ready for application consisting of a sheet 45 of flexible roofing material or fabric therefor having secured to one edge portion a strip of reinforcing sheet metal bent to overlie both sides of said edge portion, and to form a permanent angle.

50 2. As an article of manufacture a roof flashing element formed prior to and ready

for application consisting of a sheet of flexible roofing material or fabric having secured to one edge portion a strip of reinforcing sheet metal bent to overlie both 55 sides of said edge portion and to form a permanent angle, said sheet extending into said reinforcement also forming an angle therein and pinched between the sides of the reinforcement.

60 3. The method of flashing a roof which consists in providing a longitudinal opening or groove along a wall, providing a sheet of flexible roofing material or fabric with a metal reinforcement folded over the edge 65 thereof, pushing said reinforced portion into said groove, and securing it therein.

4. The method of flashing a roof which consists in providing a longitudinal opening or groove along a wall, providing a sheet of flexible roofing material or fabric with a metal reinforcement folded over the edge 70 thereof, bending said reinforcement and the sheet inclosed thereby to form a permanent angle, pushing the outer part of the said 75 reinforcement portion into said groove, and securing it therein.

5. The method of flashing a roof which consists in providing a roofing material or fabric with a sheet metal reinforcement secured to its edge and forming an angle, then 80 removing the mortar between two courses of brick, pushing the outer or edge portion of said reinforcement into the opening so formed, and securing said portion within 85 said opening.

6. The method of flashing a roof which consists in providing a sheet of flexible roofing paper with a sheet metal reinforcing member folded over the edge and flat against 90 both sides of the paper, bending the reinforcement and sheet carried thereby to form a permanent angle, removing the mortar from between two courses of brick to form 95 an opening, pushing the outer part of said reinforcement into the opening so formed, wedging said reinforcement in said opening, and then plastering up the opening.

Signed by me, this 15th day of September, 1917.

JOSEPH C. NORTON.
